UNITED STATES PATENT OFFICE.

JAMES T. HOAL, OF ATLANTA, GEORGIA.

DRILL.

1,106,306.

Specification of Letters Patent.

Patented Aug. 4, 1914.

Application filed February 17, 1913. Serial No. 748,951.

To all whom it may concern:

Be it known that I, JAMES T. HOAL, a citizen of the United States, residing at Atlanta, in the county of Fulton and State of Georgia, have invented certain new and useful Improvements in Drills; and I do hereby declare the following to be a full, clear, and exact description of the invention, such as will enable others skilled in the art to 10 which it appertains to make and use the same.

This invention comprehends improvements in rock or concrete drills and relates more particularly to those of the type which employ a reciprocating hammer actuated by any suitable power.

The primary object of the invention resides in the provision of a drill of this type, which shall be of extremely simple construction, which will be very strong and durable, and which will be especially adapted for drilling holes in concrete and similar substances.

Another important object of the invention is to provide a drill of the character described which employs a reciprocal hammer that is provided with novel means whereby desired regulation of its reciprocal movement may be had, said regulating means being held in adjusted position by novel means forming a part of the invention.

With these and other objects in view, as will become more apparent as the description proceeds, the invention consists in certain novel features of construction, combination, and arrangement of parts as will be herein-after described and claimed.

For a complete understanding of my invention, reference is to be had to the following description and accompanying drawings in which,

Figure 1 is a side elevation of my improved drill, the face plate thereof being removed and the drill shown partly in section, Fig. 2 is a longitudinal sectional view, Fig. 3 is an enlarged end elevation, partly in section, showing the hammer in its raised position, Fig. 4 is an enlarged transverse sectional view taken on the plane of line 4-4 of Fig. 2, and, Fig. 5 is a fragmentary side elevation, showing the pivot adjusting and locking means.

In the following description and accompanying drawings, similar parts will be re-

ferred to and designated by like reference characters.

Referring in detail to the drawings, A designates, generally, the body of my improved drill and is in the form of an elongated shell or housing, and comprises the member 1 and removable face plate 2. The upper end of the body or casing is formed with an internally threaded socket 3 into which one end of a tube 4 is threaded. A handle 5 is secured to the other end of the tube by means of a set screw 6. The casing is enlarged adjacent its socketed end to form the annular chamber 7 in which a wheel or disk 8 is adapted to revolve. The disk 8 is threaded upon a shaft 9 which extends outwardly through a bearing 19 formed integral with the body A. For the purpose of illustration, I have shown a crank handle 11 secured upon the outer end of the shaft 9, whereby the shaft may be rotated, but it is to be understood that any other suitable means may be employed for furnishing power to said shaft. A plurality of pins 12 are threaded into one face of the disk 8, projecting laterally therefrom, and carry the rollers 13. The pins are arranged at equal distances from each other and in a circle concentric with the shaft 9.

An eccentric pin 14 having a head 15, extends through the member 1, is squared as indicated at 16, and has its extremity reduced and threaded, as indicated at 17, to receive the nut 18. The head 15 of the pin engages the inner face of the member 1 and has a lug 19 formed eccentrically upon its other face. A bell-crank 20 is pivotally mounted intermediate its ends upon the lug 19 and is adapted to have its free arm 21 engaged by the rollers 13. To adjust the pivot point of the bell-crank, I provide a spring steel arm 22, which is fitted over the squared portion 16 of the eccentric pin. The free end of this arm is adapted to seat between any two of the lugs 23 which are arcuately formed upon the body A.

A hammer 24 is slidably mounted within the casing or body A and is formed with a head 25 upon one end. The movement of the hammer in one direction is limited by the reduced portion 26 of the body. The head moves within a cylindrical chamber 27 and an expansive spiral spring 28 surrounds the hammer, bearing against the head 25 and one end of the chamber 27. The hammer is bi-

furcated at its inner end, as indicated at 29', to receive one arm of the bell-crank 20. The bell-crank is slotted, as indicated at 29, to receive the pin 30, which has its ends fixed into 5 the hammer.

A drill chuck 31 having a flange 32 formed thereon, is slidable within one end of the body A. The chuck is adapted to hold a drill 33, which may be of any preferred construction. The flange 32 is slotted, as indicated at 34, to receive a pin 35, which pin prevents rotation of the chuck relative to the body. A sleeve 36 is threaded into the end of the body and serves to retain the chuck in 15 the proper position. The flange 32 is slid- able within a chamber 37, one end wall of which is formed by the sleeve 36.

In operation, the machine is supported in any desired manner with the drill 33 against 20 the substance to be worked. The disk 8 is rotated so as to bring the rollers 13 rapidly into engagement with the free arm of the bell-crank 20. Each roller forces the bell- crank from its path, which causes an inward 25 movement of the hammer, whereby the spiral spring is contracted. When the roller passes out of engagement with the bell-crank, the spring drives the hammer sharply against the drill chuck. This last 30 movement returns the free end of the bell- crank to the path of the rollers and the operation is repeated. The stroke of the hammer may be regulated by an adjustment of the eccentric pin and this can be easily ac- 35 complished by shifting the arm 22 to a new position, said arm being preferably formed of spring steel to permit it to be moved over the lugs 23. To increase the length of the stroke, the spring arm 22 is moved in a di- 40 rection which will move the free arm 21 of the bell-crank 20 farther into the path of travel of the rollers 13 whereby a greater bearing surface therefor is afforded by the arm 21 and the adjusted position of the arm 45 21 is maintained by allowing the spring arm to fit between the lugs 23 formed on the casing. It will thus be seen that the length of the stroke of the hammer may be regulated to the desired degree by the 50 above described means. This means of adjustment I consider to be one of the primary features of my invention.

From the foregoing description taken in connection with the accompanying drawings, it will be seen that I have designed a drill in which the hammer may be very rapidly reciprocated with the use of the minimum amount of power. It is to be understood that while I have shown and de- 55 scribed the preferred embodiment of my invention, I do not wish to be limited to this exact construction, combination, and arrangement of parts, but may make such changes as will fall within the spirit and 60 scope of the invention.

Having thus described my invention, what I claim is:—

1. In a drill of the character described, the combination of a casing, a rotatable member journaled therein, a bell-crank, means carried by said rotatable member for rocking said bell-crank, an eccentric pin forming a pivotal support for the bell-crank, an arm fixed to said pin to turn the same, means for locking the arm in any desired position, comprising a plurality of arcuately arranged spaced lugs formed upon said casing, a hammer pivotally secured to and actuated by said bell-crank, spring means mounted upon said hammer for holding said hammer in its normal outermost position and a drill chuck adapted to be engaged by 70 said hammer.

2. A drill consisting of a casing, a pin rotatably secured in an opening formed in 85 the wall thereof, means for rotating said pin, an eccentric lug formed upon the inner end of said pin, a bell-crank pivotally mounted on said eccentric lug, a hammer reciprocatingly mounted within said casing 90 and operably secured to said bell-crank, spring means mounted upon said hammer for holding said hammer in its normal outermost position, said pin being squared for a portion of its length, an arm fitted upon said 95 squared portion, means for holding said arm thereon, a plurality of lugs arcuately arranged upon said casing, said arm being adapted to fit between certain of said lugs whereby an adjustment of the length of the 100 stroke of said hammer is facilitated.

3. In a device of the character described the combination with a casing, of a hammer reciprocatingly mounted therein, means for reciprocating said hammer mounted within 105 said casing comprising a spring mounted upon said hammer, a bell-crank pivoted upon the upper terminal of said hammer, an annular disk rotatably mounted within said casing, a plurality of pins mounted in 110 spaced relation upon said disk and adapted for engagement with the bell-crank, and an exteriorly operable crank handle secured to said disk and means for regulating the reciprocal action of said hammer comprising a spring arm operatively connected with the bell-crank and means for locking said 115 last named means in adjusted position formed integrally with the casing upon the outer side thereof and adapted for en- 120 gagement with said arm.

4. In a device of the character described the combination with a casing of a hammer reciprocatingly mounted therein, means for reciprocating said hammer including a 125 spring, a rotatable member journaled within said casing, a plurality of spaced pins mounted upon said rotatable member, a bell-crank operatively connected with the hammer and a crank handle operatively 130

connected with the rotatable member, and means for regulating the reciprocal movement of said hammer comprising a pin rotatably mounted in said casing, an eccentric 5 lug formed on the inner end of said pin and operatively connected with the bell-crank, a spring arm secured to the outer end of said pin, means for securing said spring arm to said pin and means for locking said

spring arm in adjusted position comprising 10 a plurality of integrally formed and arcuately arranged lugs carried by said casing.

In testimony whereof I affix my signature in presence of two witnesses.

JAMES T. HOAL.
